(57) **CLAIM**

The ornamental design for a wreath greeting card, as shown and described.

DESCRIPTION

FIG. 1 is a front perspective view of a first embodiment of the greeting card of the present invention, in a closed position.

FIG. 2 is a front view of the greeting card of FIG. 1.

FIG. 3 is a rear view of the greeting card of FIG. 1.

FIG. 4 is a right side view of the greeting card of FIG. 1.

FIG. 5 is a left side view of the greeting card of FIG. 1.

FIG. 6 is a top down view of the greeting card of FIG. 1. FIG. 7 is a bottom up view of the greeting card of FIG. 1; and,

FIG. 8 is a front perspective view of the greeting card of FIG. 1, in a partially open position.

The broken line showing of portions of the wreath greeting card is included for the purpose of illustrating environment and forms no part of the claimed design.
